(57) **CLAIM**

I claim the ornamental design for a sliding window shelf, substantially as shown and described.

DESCRIPTION

FIG. 1 is a perspective view of a sliding window shelf in a closed configuration.

FIG. 2 is an perspective view of a sliding window shelf in an open configuration.

FIG. 3 is a front view of a sliding window shelf in a closed configuration.

FIG. 4 is a front view of a sliding window shelf an open configuration.

FIG. 5 is a right-side view of a sliding window shelf on a bracket mounted to a wall.

FIG. 6 is left-side view of a sliding window shelf on a bracket mounted to a wall.

FIG. 7 is a top view of a sliding window shelf an open configuration.

FIG. 8 is a bottom view of a sliding window shelf an open configuration.

FIG. 9 is a top view of a sliding window shelf in a closed configuration; and,

FIG. 10 is a bottom view of a sliding window shelf in a closed configuration.

The features shown in broken lines in the various Figures are for illustrating environmental structure and form no part of the claimed design. The sliding window shelf is shown with a symbolic break in its width and length. The appearance of any portion of the article between the zig-zag break lines of the figures forms no part of the claimed design.

The article of manufacture and design can be scaled to different sizes. As indicated above, the article of manufacture is a sliding window shelf.

1 Claim, 5 Drawing Sheets
